Primary Examiner — Alison M Ofstun(74) *Attorney, Agent, or Firm* — Norman E. Lehrer(57) **CLAIM**

The ornamental design for an electric shaver foil head, as shown and described.

DESCRIPTION

FIG. 1 is a bottom side perspective view of an electric shaver foil head showing my new design;

FIG. 2 is a top side perspective view thereof;

FIG. 3 is a top plan view thereof;

FIG. 4 is a bottom plan view thereof;

FIG. 5 is a right side elevational view, the left side elevational view being identical thereto; and,
FIG. 6 is a front elevational view, the rear elevational view being identical thereto.

The portions shown in broken lines are for environmental purposes only and form no part of the claimed design.
